(57) **CLAIM**

The ornamental design for a toothpaste dispensing toothbrush, substantially as shown.

DESCRIPTION

FIG. 1 is a perspective view showing a toothpaste dispensing toothbrush according to my new design;

FIG. 2 is a similar perspective view thereof, showing the toothpaste-storing handle separated from the head portion thereof;

FIG. 3 is a side view thereof, the opposite side being similar;
FIG. 4 is a frontal view thereof;

FIG. 5 is a bottom view thereof; and,

FIG. 6 is a top view thereof.
